UNITED STATES PATENT OFFICE.

RALPH D. CRAWFORD, OF MAMARONECK, NEW YORK.

AUTOMATIC STOKER.

Application filed January 18, 1928. Serial No. 247,568.

My improvements are directed particularly to stokers which are adapted for feeding coal from a reservoir or hopper, by mechanical means and in connection with a forced draft, 5 to a fire pot or similar place of combustion; and objects of my invention are to provide means whereby the coal dust thrown into the air during the process of dumping coal in the hopper shall be prevented from escaping into 10 the surrounding air and shall be carried forward to the fire pot through the same channels which convey the coal, thus increasing the neatness of operation of the stoker; also, to 15 accomplish these results by the same means which create the forced draft utilized with the stoker, thus simplifying the mechanism and avoiding duplication of operative means.

In the accompanying drawings, in which I 20 have shown my improvements as applied to an underfeed stoker adapted for use in the smaller classes of furnaces, such as are used for heating residences and the like, Fig. 1 is an elevation of an apparatus embodying my invention partially broken away to show interior construction; Fig. 2 is another elevation taken as looking to the right on Fig. 1, the fire pot being omitted; Fig. 3 is a plan view; and Fig. 4 is a sectional view, taken on the line 4—4 of Fig. 2, looking down, part of 25 the feed-chute and air duct being broken away to show the interior construction.

A hopper 1 is provided with a sloping bottom 2, leading to an outlet 3, connecting with a tubular duct 4, provided with a feed-worm 35 5, journaled in bearings as 6 at the fire-pot end and 7 at the opposite end. An electric motor 8 is provided with a shaft 9, carrying a worm 11, meshing with a worm gear 12, which through its shaft 13 and arm 14, connecting rod 15, arm 16 and pawl 17, engaging 40 with ratchet wheel 18 on the end of the worm shaft 19, rotates the worm step by step to force coal, for instance such as the grades called "buckwheat", supplied through the 45 outlet 3, to the fire pot 21, in an underfeed manner.

A conventional blower fan element 23 is 50 driven by the shaft of the motor 8, and its discharge is connected, by a pipe 24, with a pipe 10 jacketing the duct 4, so that the air driven forward by the fan is forced along the pipe 10 to the fire pot, where part of the air passes into the fire, through the holes 22, 22, and

part rises around the fire pot to assist in the process of burning the gases evolved in the 55 fire pot.

The fire pot 21 may be placed within the fire box of a furnace, or in any place suitable to utilize the evolved heat, as will be readily understood by those familiar with the art. 60

These portions of the apparatus are old; and they are shown and explained simply to make clear the application of my improvements.

The fan element 23 is provided with a centrally disposed inlet opening within a neck 25 shown in broken line in Figs. 2, 3 and 4. Over this neck I place a sleeve 26, preferably provided with a rose damper 27, and connected with a pipe 28 extending up to and connected through the overhanging bottom 29 of a hood 30 partially covering the top of the hopper 1 at one end. This hood 30 is closed above and at its sides 31, 32, but its bottom over the hopper is open, although that portion 75 of the bottom extending beyond the side of the hopper is closed.

A downwardly deflected flange 33 is preferably carried around the inner sides of the hopper 1, not covered by the hood, its ends 80 being continued under the hood. The width and angle of this flange may be varied, as circumstances may indicate. But it should not be sufficiently wide to materially interfere with shoveling coal into the hopper. 85

With the fan element 23 in operation, and the rose damper 27 closed, air will be drawn from within the hood 30 and forced through the air pipe 10 to the fire pot. Then if coal is shoveled into the hopper 1, the suction of 90 the fan 23 will draw the dust incidentally developed in the hopper along under the flange 33 and generally under and then upward out of the hood 30 and force it towards the point of combustion. The draft produced by the 95 fan will be sufficient to quite effectually control the coal dust ordinarily evolved in filling the hopper, and to eliminate the diffusion of such dust outside of the hopper and stoking apparatus; thus greatly increasing the desirability of the stoker for domestic and similar uses. 100

When the supply of coal in the hopper is not being renewed, the rose damper may be opened, if desired, and outside air supplied 105 directly to the fan; although if the air con-

tinues to be drawn from the pipe 28, any incidental dust caused by the shifting of the coal in the hopper 1 in the process of feeding will be sucked up and prevented from spreading outside of the apparatus.

By this arrangement I am able practically to eliminate annoyance from dust diffused from the hopper during the process of supplying it with coal; and to do this by utilizing the forced draft mechanism without the aid of other power units or increased expenditure of power.

I desire it to be understood that the apparatus I have shown and explained is to be regarded as an illustrative and not an exclusive embodiment of my invention; for it is obvious that details may be modified, as by the use of mechanical equivalents and the like, without departing from the spirit of my invention and the scope of the claims.

Having thus described my invention, what I claim and desire to secure by Letters Patent of the United States is:—

1. In an under-feed stoker for broken coal of the character described, the combination with a coal hopper provided with an open top to admit coal, of a dust hood partially above the open top, a fire pot, a coal duct, a feed screw in the coal duct to carry the coal from the hopper to the fire pot, a blower, an air duct, independent of the coal duct, from the blower to the fire pot, and a

blower to the fire pot, and a dust duct extending from the hood to the blower intake.

2. In an under-feed stoker for broken coal of the character described, the combination with a coal hopper provided with an open top to admit coal, of a dust hood partially above the open top, a downwardly and inwardly sloping interior flange around the uncovered edges of the open top, a fire pot, a coal duct, a feed screw in the coal duct to carry the coal from the hopper to the fire pot, a blower, an air duct, independent of the coal duct, from the blower to the fire pot, and a dust duct extending from the hood to the blower intake.

3. In an under-feed stoker for broken coal of the character described, the combination with a coal hopper provided with an open top to admit coal, of a dust hood partially above the open top and having an end projecting beyond the hopper, a downwardly and inwardly sloping interior flange around the uncovered edges of the open top, a fire pot, a coal duct, a feed screw in the coal duct to carry the coal from the hopper to the fire pot, a blower, an air duct, independent of the coal duct, from the blower to the fire pot, and a dust duct extending from the projecting end of the hood to the blower intake.

RALPH D. CRAWFORD.
